US0D1059838S

(12) **United States Design Patent** (10) **Patent No.:** **US D1,059,838 S**
(45) **Date of Patent:** **** Feb. 4, 2025**

(54) **ORGANIZING GRID FOR STORAGE CASE**

(71) Applicant: **Magpul Industries Corp.**, Austin, TX (US)

(72) Inventors: **Timothy Eric Roberts**, Broomfield, CO (US); **Michael Werner**, Arvada, CO (US); **Clinton Wade Lynch**, Erie, CO (US); **Jacob Blick**, Superior, CO (US); **Kellen Cooper Sansone**, Denver, CO (US)

(73) Assignee: **Magpul Industries Corp.**, Austin, TX (US)

(**) Term: **15 Years**

(21) Appl. No.: **29/852,614**

(22) Filed: **Sep. 8, 2022**

(51) LOC (15) Cl. **03-01**

(52) U.S. Cl.

USPC **D3/262**; D9/456

CLAIM

The ornamental design for an organizing grid for storage case, as shown and described.

DESCRIPTION

FIG. 1 is a left, front, top perspective view of an organizing grid for storage case;

FIG. 2 is a front elevation view thereof;

FIG. 3 is a rear elevation view thereof;

FIG. 4 is a left elevation view thereof;

FIG. 5 is a right elevation view thereof;

FIG. 6 is a top view thereof; and,

FIG. 7 is a bottom view thereof.

The dash-dash broken lines depict portions of the organizing grid for storage case that form no part of the claimed design. The remaining dash-dot broken lines depict claim boundary limits and form no part of the claimed design.

1 Claim, 6 Drawing Sheets
